UNITED STATES PATENT OFFICE

2,537,861

COMBINED WINDOW SCREEN, SUNSHADE,
AND AIR DEFLECTOR

William Maurice Routson, Baltimore, Md.

Application August 22, 1947, Serial No. 770,117

5 Claims. (Cl. 98—44)

1

The invention aims to provide a novel and advantageous device which will perform much the same function as a window awning when in certain positions, and may be positionally adjusted to deflect air currents inwardly through the window for room cooling and ventilating, and I prefer to also include a window screen with the other structure.

Figure 1 of the accompanying drawings is an outer side elevation of the device with the hood positioned to act as an ordinary awning.

Fig. 2 is an edge view as seen from the right of Fig. 1.

Fig. 3 is an enlarged vertical sectional view, partly broken away, substantially on line 3—3 of Fig. 1.

Figs. 4 and 5 are enlarged detail horizontal sectional views on the correspondingly numbered lines of Fig. 1.

Fig. 6 is an inner side elevation of the plate upon which the arcuate track is mounted.

Fig. 7 is a detail section on line 7—7 of Fig. 6.

Fig. 8 is a detail section similar to the upper portion of Fig. 3 but showing a variation of construction.

Preferences have been illustrated in the drawings and will be rather specifically described, but attention is invited to the possibility of making numerous minor variations within the scope of the invention as claimed.

A window screen 10 is shown having a wooden frame 11, although a metal frame could of course be used. This frame comprises parallel vertical side bars 12 and parallel upper and lower bars 13 and 14, and I provide said frame with an additional vertical bar 15 disposed centrally between the side bars 12 and secured at its ends to the bars 13 and 14.

A horizontal bearing sleeve 16 is secured in an opening in the bar 15 and extends from the inner side to the outer side of this bar, and in the construction shown, nuts 17 are threaded onto the ends of said bearing sleeve to secure it in place. I have shown the outer end of the sleeve extending through the screen 10, and the outermost nut 17, therefore, abuts this screen whereas the inner nut simply abuts the bar 15.

A short shaft 18 extends rotatably through the bearing sleeve 16 and is provided at its outer end with a flange or hub 19. An operating knob 20 is suitably secured upon the inner end of this shaft 18, in inwardly spaced relation with the sleeve 16, and a lock nut 21 is threaded on said shaft between said knob and sleeve. When this lock nut is tightened, it draws the flange or hub 19 tightly

against the outer end of the bearing sleeve 16 and holds the shaft 18 against rotation, but loosening of said lock nut permits easy turning of said shaft by means of the knob 20.

5 Suitable radial spokes 22 are bolted or otherwise secured to the flange or hub 19, and these spokes carry a hood 23, said hood having an arched truly arcuate inner end 24. The hood 23 is open at its lower side as seen at 25 in Fig. 3, and said hood is also open at its inner end. Thus, when the hood is turned to proper position, by turning the knob 20, it will deflect an air current at the outer side of the building, inwardly through the screen 10, for the purpose of room cooling or ventilating, and when said hood is positioned as shown in the drawings, it acts much the same as a conventional awning.

In the construction disclosed, an arcuate guide flange 26 is riveted or otherwise secured at 27 to the outer side of the hood 23 and extends along its arcuate inner end portion 24. Bolts 28 are shown extending through the flange 26 and hood 23 and securing this hood to the outer ends of the spokes 22.

25 An arched arcuate track 29 is carried by the frame 11 to guide the flange 26, said track being shown as composed of suitable sections assembled into channel form, the channel receiving said flange 26. I have shown a screw 30 securing the crown of the track 29 to the upper frame bar 13, and other screws 31 securing the ends of said track to the side bars 12, but bolts could of course be used instead of screws if desired.

In the construction shown, a flat vertical plate 32 is interposed between the track 29 and the frame 11 to close the spaces between said track and the upper corner portions of said frame. This plate is formed with an arcuate lower edge 33 following the curvature of the track 29, and said plate may well be secured to said track by rivets or the like 34. The upper and vertical edge portions of the plate are secured to the outer side of the frame 11 by screws or other fasteners 35.

45 A short arcuate track 36 of channeled form, is suitably secured to the lower bar 14 of the frame 11, to receive the flange 36 of the hood 23 in certain positions of said hood. The ends of this track are preferably flared as shown at 37 and the ends of the track 29 are similarly flared as illustrated at 28, the track ends being thus prevented from binding upon the flange 26 as the latter slides in the tracks.

50 In Fig. 8, I have shown a somewhat different construction in which the hood 23a is provided with an inwardly turned flange 26a engaging a

channeled track 28a. When this construction is used, the inner end of the hood will be hung and thus the entire weight of said hood will not be supported by the central shaft and bearing.

From the foregoing, taken in connection with the accompanying drawings, it will be seen that novel and advantageous provision has been made for providing a window with a sun shade, and for inwardly directing air currents through the window whenever the hood is turned to a position in which its open side will face an air current. Also, when a screen is embodied in the structure, a combined screen, sun shade and air deflector results, and the unit thus formed may be easily mounted at a window, for instance, by substituting it for a lower storm sash.

As excellent results may be obtained from the structure disclosed, it may be considered as preferred as above stated, but attention is again invited to the possibility of making variations within the scope of the invention as claimed. For example, by providing in any way a light reflecting surface on the inner face of hood 23, the device will reflect light into the room.

I claim:

1. A combined sun shade and air deflector comprising a vertical frame to be mounted at a window, said frame having parallel vertical side bars, parallel upper and lower bars, and an additional bar disposed between two of said parallel bars and secured at its ends to the other two of said parallel bars; a horizontal bearing secured to said additional bar between the ends of the latter, a shaft extending through said bearing from the inner to the outer side of said frame, the outer end of said shaft having a hub and the inner end of said shaft being provided with a knob, spokes secured to said hub and radiating therefrom toward said side bars and said upper bar, and a hood at the outer side of said frame and secured to said spokes, said hood having an arched inner end adjacent said frame, said hood being open at its lower side and at said inner end to permit it to deflect an air current inwardly through said frame when said hood is turned to a position in which said open side faces the air current.

2. A structure as specified in claim 1; together with an arched arcuate track secured to said frame at the inner end of said hood, said hood having guide means engaging said track.

3. A structure as specified in claim 2; together with a short arcuate track secured to said frame below said hood in position to be engaged by said track-engaging means of said hood when the latter is turned to an extreme position.

4. A combined sun shade and air deflector comprising a vertical frame to be mounted at a window, said frame having parallel vertical side bars and parallel upper and lower bars; a vertical auxiliary bar midway of the width of the frame, a bearing mounted horizontally through the

auxiliary bar midway of the upper and lower ends, an arched arcuate track secured at its crown to said upper bar and secured at its ends to said side bars, a second arcuate track secured to the lower bar, and a hood at the outer side of said frame and having an arched inner end substantially co-extensive with the first mentioned track, a shaft carried by said hood midway of the width of the lower end thereof and rotatably mounted through said bearing and having a turning member at its inner end, a nut carried by said shaft for engaging the inner end of said bearing and releasably holding the shaft and the hood in a turned position of adjustment, said hood having means engaging said tracks to guide said hood when it is turned about the bearing, said hood being open at its lower side and at its inner end to permit it to deflect an air current inwardly through said frame when said hood is turned to a position in which its open side faces the air current.

5. A combined sun shade and air deflector comprising a vertical frame to be mounted at a window with a screen covering said frame, said frame having parallel vertical side bars and parallel upper and lower bars; a plate disposed in a vertical plane at one side of said frame, said plate being secured against said upper bar and the upper end portions of said vertical side bars and having arched arcuate lower edge, an arched arcuate track secured against one side of said plate and extending along said arched arcuate lower edge of the latter, a tubular bearing supported by said frame and extending through said screen concentric with said track, a hood at the outer side of said frame and having an arched inner end substantially co-extensive with said track, a shaft extending through and rotatable in said bearing, means rigidly connecting the inner portion of said hood to the outer end of said shaft, said hood having means along its arcuate inner end engaging said track to guide said hood when it is turned about the bearing, said hood being opened at its lower side and at its inner end to permit it to deflect an air current inwardly through said frame when said hood is turned to a position in which its open side faces the air current.
